UNITED STATES PATENT OFFICE.

JOSEPH MALBOEUF, OF WOONSOCKET, RHODE ISLAND.

SUSPENDED SWINGING FLATIRON.

Application filed October 21, 1927. Serial No. 227,645.

This invention relates to a new and useful device in the nature of a suspended flatiron adapted for use in ironing or pressing clothes, or the like.

5 The object of the invention is to provide a novel means of suspending the flatiron, so as to relieve the person ironing from the necessity of lifting the said iron.

A further object of the invention is to 10 provide a suspended iron of novel construction and arrangement of parts hereinafter more fully described, claimed, and illustrated in the accompanying drawing.

Fig. 1 is a side elevational view of my improved device, partly in section so as to clearly show the construction involved.

Fig. 2 is a top plan view thereof.

Fig. 3 is an enlarged fragmentary side elevational view partly in section.

20 Fig. 4 is a fragmentary sectional view taken on the line 4—4 of Fig. 3.

In Fig. 1 of the accompanying drawing, I have shown a table 10, supported by the legs 11, attached thereto, and extended downwardly therefrom. The top 10, is adapted to support the ironing board 12, which is held in a raised or upper extended position therefrom by the supporting members 13, the above described elements being those, 25 such as commonly used for ironing or pressing. It should be understood that I do not necessarily limit the use of my invention to the particular type of ironing board and table as above described, but to all classes 30 and types of ironing boards, and tables, such as generally used for the purpose of ironing or pressing.

As here embodied my improved device 35 comprises a base member 14, secured to the upper side of the top of the table 10, by the threaded members 15, bolts, screws, or the like. The upright members 16 are secured to the base member 14, and are extended upwardly therefrom. The ring member 17 is secured to the upper extended extremities of the upright members 16. The upper upright members 18 are secured to the ring member 17 and are extended upwardly therefrom. The upper ring member 19 is 40 secured to the upper extended extremities of the upper upright members 18.

The base member 14 is provided with an enlarged central portion 20 having formed therein a threaded aperture, adapted to receive the threaded lower portion 21 of the supporting member 22 extended vertically

therefrom. The hand wheel 23 is threadedly attached to the threaded portion 21 of the supporting member 22 and is positioned directly above and in contact with the upper surface of the enlarged central portion 20 of the base member 14. The above described construction is such as will permit the supporting member 22 to be extended upwardly for the purpose as hereinafter set forth, 60 when the hand wheel 23 is rotated or turned.

The upper extended extremity of the supporting member 22 is provided with an enlarged portion 24 having formed therein a semi-circular recess adapted to receive the 65 enlarged spherical extremity 25 of the arm 26. The cap 27 is provided with a semi-spherical aperture and communicative opening adapted to receive the spherical extremity 25 of the arm 26. The cap 27 is secured 70 as at 28 by bolts, screws, or the like, to the enlarged portion of the supporting member 22. The arm 26 is provided with a horizontally extended portion 29. The flexible member 30, preferably a chain, is attached 75 to the free extremity of the extended portion 29. The tension spring 31 is attached to the lower extremity of the flexible member 30 and to the handle 32 of the flatiron 33. The flatiron 33 is of common construction, 80 such as generally used for ironing or pressing clothes, and may be gas or electrically heated. The flexible tube 34 or electric cable, is attached to the flatiron 33 and to any suitable convenient source of gas supply 85 or electric current, not shown in the accompanying drawing. The wire 35 is attached to the extended portion 29 of the arm 26, and is provided with a hook 90 36 at the lower extremity of the wire 35, and 95 is adapted to engage the flexible tube 34, or electric cable, so as to hold the said flexible tube or cable so as to eliminate interference with the person using the said flatiron.

100 The above described construction is such as will permit the extended portion 29 of the arm 26 to be pivotally supported by the supporting member 22. It should be understood that the said extended portion 29 of the arm 26 is supported by the upper ring member 19, the hand wheel 23 being rotated, or turned, so as to secure the proper position of the said extended portion.

110 The yoke member 37, is pivotally attached intermediate the extended portion 29 of the arm 26 as at 38, by a pin, or the like, so as

to be capable of assuming slightly inclined positions relative to the portion 29, desirable when the portion 29 is tilted as shown in Fig. 3. It should be understood that when the arm 26 is vertical, the yoke member 37 is parallel to the arm, but when the arm 26 is inclined the yoke member 37 will not be truly parallel. The yoke member 37 is provided with a pointed lower extremity 39, adapted to engage in a circular recess 40 formed in the ring member 19. The above described construction is such as will permit the extended portion 29 of the arm 26 to be held in any desired upper angular extended position, as designated by the reference numeral 41, or in any desired downwardly angularly extended position as shown in Fig. 3 of the accompanying drawing. The said angular positions are secured by rotating or turning the above mentioned hand wheel 23 for raising or lowering the spherical extremity 25, and thus tilting the arm 29 about the yoke member 37. The above described construction is such as will permit the flatiron 33 to be held in any desired suspended position relative to the ironing board 12 so as to facilitate the use of the said flatiron.

Having thus described my invention what I claim as new and desire to protect by Letters Patent of the United States is as follows:

1. In a device of the class described, an upper ring member, upright members connected to support the said upper ring, an arm provided with an extended portion supported by the upper ring member, a supporting member pivotally attached to the arm, a

means for extending the supporting member, and a flatiron suspended from the said extended portion of the arm. 40

2. In a device of the class described, an upper ring formed with a circular recess, upright members connected to support the said upper ring, an arm provided with an extended portion, a yoke member pivotally attached intermediate of the ends of said extended portion, and being provided with a pointed extremity engaging in the said circular recess for supporting the extended portion, a supporting member pivotally attached to the arm, a means for extending the supporting member, and a flatiron suspended from the said extended portion of the arm. 45 50 55

3. In a device of the class described, an upper ring formed with a circular recess, upright members connected to support the said upper ring, an arm provided with an extended portion, a yoke member pivotally attached intermediate of the ends of said extended portion, and being provided with a pointed extremity engaging in the said circular recess for supporting the extended portion, a supporting member pivotally attached to the arm, and provided with a threaded lower portion, a base member engaged by the said threaded lower portion, and a hand wheel threadedly engaging the said threaded lower portion for acting as a means for extending the supporting member, and a flatiron suspended from the said extended portion of the arm. 60 65 70

In testimony whereof I have affixed my signature.

JOSEPH MALBOEUF.
